UNITED STATES PATENT OFFICE

THEODORE J. GARISIO, OF ALLENTOWN, PENNSYLVANIA

LOOM

Application filed May 16, 1930. Serial No. 453,052.

My invention relates to looms for weaving silk fabrics, from sheer chiffon to heavy count crepe, and has for its object to avoid the so-called "barre" effect in these fabrics.

5 While this defect is not so noticeable in the raw silk fabric, it is quite prominent after the goods have been dyed, and is the cause of rejection of large quantities of woven silk.

10 By my invention this defect in the fabric is avoided, and it comprises the reed mounting of these looms, by which the reed is pivoted below its bottom and is under spring tension.

15 Silk looms having reeds pivoted at their top are now in general use, but such structures do not prevent "barre".

Referring to the drawings in which like parts are similarly designated—

20 Figure 1 is a front elevation of my improved structure.

Fig. 2 is a side elevation thereof.

Fig. 3 shows a modified arrangement using a leaf spring instead of a coil spring.

25 Fig. 4 shows a still further modification, using a compression coil spring.

Fig. 5 shows a further arrangement, using a shortened lever.

Referring to Figures 1 and 2, I have shown 30 only so much of the usual silk loom as is necessary to an understanding of my invention, and in which 10 are the swords, 11 the bolt to which the crank rod for swinging the swords to and fro is connected, 12 the sword eye to which the sword is bolted or made in

35 one piece therewith in some looms, and 13 is the sword pivot, usually a shaft. At the top the swords are connected together by a bridge rail 14 adjustable vertically by bolts 15 passing through upright slots in the top of the swords. This rail 14 is usually angular in

40 section, as shown in Fig. 2.

The reed structure including the upper and lower reed rails 16 and 17 respectively, is strengthened by angle irons 18 to prevent warping; each upper and lower reed rail contains a grooved reed cap 19, and in the grooves of these caps the upper and lower edges of the reed 20 are seated.

45 The upper ends of the swords have an

opening 21 through them; 22 is the usual batten, and 31 is the glass friction rod for the warp.

50 So much of the loom is found in present day silk looms.

55 My invention may be attached to present silk looms or may be built into the loom.

The swords are drilled with alined holes at the recesses 21 below the reed 20, and I utilize the present recesses for securing the ends of a stationary shaft 23 in the drilled holes by passing a screw 24 diagonally through the ends of the shaft with their ends resting in the bottom of the recesses 21. The screw in one recess is inclined in an opposite direction to that in the other recess to hold the shaft from rotating. Any other means for fixing the shaft may be used, or in lieu of the shaft I may use stub shafts or bolts, but I prefer a continuous shaft, as shown.

60 On this shaft I mount at each of its ends a lever 25 on antifriction bearings, preferably roller bearings 25^a, so that the two levers 25 are carried by the swords 10 and pivot on the shaft. The upper end of each lever is approximately fork-shaped, by reason of extensions 26 and 27 perpendicular to the plane of the reed, and the reed rails 16 and 17 extend from these two extensions parallel to the reed, as at 28 and 29, Figs. 1 and 2.

65 Each lower extension 29 has adjacent its lever a hook 30 for holding the usual glass friction rod 31 for the warp. Each of these extensions, 28 and 29 has vertical slots 32 through which pass the bolts 33 that secure the reed rails 16 and 17 onto them and by which the rails can be vertically moved to adjust the height of the reed 20. Below the pivot shaft 23 the lever has a lug 34 that strikes against the bent end of stop pin 35, whose shank passes through the sword and is held by a nut 36. By this lug and pin the forward limit of the reed with respect to the swords and the fabric can be adjusted.

70 Each lever has a forwardly and downwardly inclined arm 37 between its pivot point and the lower end, which arm is provided with notches or serrations 38, Fig. 2, on its upper edge.

75 Adjustable to any one of the notches 38 is

a link 39 in which is hooked the upper end of a coil spring 40. The lower end of the spring 40 hooks into an eye 41 at the upper end of a rod 42 whose lower end is threaded and passes through a trunnion block 43 and is held therein by nut 44. The trunnions 45 of this block engage in a hook shaped casting 46 secured to the side, front or back of the sword.

The operation is as follows:

10 As the swords come forward to beat up the pick the reed will be stopped against the pick, while the swords continue to move forward a short distance to the end of their stroke, and the reed remains against the pick for a 15 short time, and also for a short time at the beginning of the rearward stroke, during which the new shed of the warp is beginning to be made.

10 The resistance of the reed can be regulated 20 by shifting the link 39 along the downwardly inclined arm 37 within limits to increase or decrease the tension of spring 40 during weaving.

An initial or major adjustment of the tension of the spring can be made by increasing or decreasing the effective length of the spring by nuts 44.

15 The stop at 34, 35 is a positive limit for the forward position of the reed with respect 25 to the swords.

It is, of course, known that natural ray silk fiber is not of uniform diameter, and with the smaller denier filling threads for sheer fabrics this may play an important role 35 in producing the barre effect.

It may be that when the reed is pivoted at the top it depresses the lower shed slightly at the pick and the warp has a very little more tension as the reed holds the pick for 40 a moment as the shed begins to change, and the pick is gripped by the shed at a point slightly below the proper fabric level and is forced out of place at the beginning of the shedding operation.

45 However, no one knows the cause of the defect, but whatever the cause, my invention remedies barre, and with it I weave perfect fabrics without any trouble whatever.

While the structure shown in Figs. 1 and 50 2 is the preferred form of my invention, other structures are useful to the same end.

In Fig. 3 I have shown the lower end of the lever 48 having fastened to it a leaf spring 49. The lower end of this spring seats loosely between lugs 50, or it may be in a pocket projecting from the side of the sword 10.

55 In Fig. 4 I have shown the lever 51 having a rearwardly projecting arm 52 having 60 a bolt 53 on which is mounted an eye 54 on the upper end of a rod 55 whose lower end slides loosely through an eye 56 on the sword. The lower end of the rod 55 is threaded and provided with a nut 57. On the rod 55 is 65 a spring 57^a under compression between the

eye 56 on the sword and a collar 58 adjustably held on the rod 55 by a set screw 59.

In Fig. 5 I have shown the simplest form, 70 in which the lever 60 is a one-armed lever, instead of having two arms, as in the previous figures. In this case the pivot shaft 23 has a collar 61 held to the shaft by a set screw 62. The upper end of a spring 63 rests loosely against the upper end of the lever 60, and its lower end is coiled to surround the pivot shaft 23, and its extremity enters a hole in collar 61.

75 By loosening the collar and turning it on the shaft and then clamping the collar to the shaft by the set screw, the tension of the spring can be changed. The upper ends of levers 48, 52 and 60 are the same as lever 25.

I claim—

80 In a loom, the combination with the swords and reed structure; of a stationary shaft carried by the swords below the reed structure, 85 a lever for each sword pivoted on the shaft, said reed structure mounted on its ends between the upper ends of the levers, a downwardly inclined notched arm extending from each lever from a point below its pivot, a 90 link adjustable along said arm, a spring whose upper end engages the link, a pivot block mounted on the sword, and means to adjustably connect the lower end of the 95 spring to said block.

95 In testimony that I claim the foregoing as my invention, I have signed my name hereto.

THEODORE J. GARISIO.
